DESIGN FOR A BROOCH PIN OR SIMILAR ARTICLE

Arthur Godwin, St. Paul, Minn.

Application February 21, 1941, Serial No. 99,163

Term of patent 7 years

To all whom it may concern:

Be it known that I, Arthur Godwin, a citizen of the United States, residing at St. Paul, in the county of Ramsey and State of Minnesota, have invented a new, original, and ornamental Design for a Brooch Pin or Similar Article, of which the following is a specification, reference being had to the accompanying drawing forming part hereof.

The essential features of my design are shown in full lines, the broken lines shown in Figure 1 have been omitted from Figures 2 and 3 for convenience of illustration. My design for a brooch pin or similar article, as shown, is characterized by the relative proportions of the three elements and the specific placement of the same.

I claim:

The ornamental design for a brooch pin or similar article, substantially as shown and described.

ARTHUR GODWIN.
